(57) **CLAIM**

The ornamental design for an ink cartridge, as shown and described.

DESCRIPTION

FIG. 1 is a perspective view of an ink cartridge;

FIG. 2 is a front view thereof; and,

FIG. 3 is a top view thereof.

The broken lines are for illustrative purposes only and form no part of the claimed design.

1 Claim, 2 Drawing Sheets

FIG. 1

FIG. 3

FIG. 2
